Primary Examiner — Ismael Izaguirre(74) *Attorney, Agent, or Firm* — Corridor Law Group, P.C.(57) **ABSTRACT**

An outfit hanger and display has a head section, a shoulder section, a torso section, a bottom (hip/waist) section, a neck section, an arm section, and a hand section. In some embodiments the head section has a loop, a hanging hook and an earring section. The earring section can be made of, among other things, a polystyrene foam, a magnetic material, a plastic material, or an adhesive material. In some embodiments the torso section is expandable. In some embodiments the hanger has a necklace/scarf guide that can be used to display necklaces or scarves on the hanger. In some embodiments, the outfit hanger has at least one stabilizing foot.

OUTFIT HANGER AND DISPLAYER

CROSS-REFERENCE TO RELATED APPLICATIONS

This application is related to and claims priority from U.S. Provisional Application No. 62/111,003 filed Feb. 2, 2015 entitled "Outfit Hanger and Display". The '003 application is hereby incorporated by reference in its entirety.

FIELD OF THE INVENTION

The present invention relates to clothes hangers and displayers. More specifically, the invention relates to an outfit hanger that can be used to display multiple parts of an outfit (tops, bottoms, and accessories).

BACKGROUND OF THE INVENTION

Many individuals use hangers to store their clothes. Hanging clothes helps prevent the clothes from wrinkling and/or being damaged. Hanging clothes is often preferred over putting clothes in dressers and/or trunks since clothes that are hung, tend to be easier to access and also tend to have less wrinkles than clothes placed in dressers.

Traditional hangers are limited in that they can only hold and/or display one or two pieces of clothing. In addition, traditional hangers do not have a way to display and/or store various accessories such as, but not limited to, jewelry (including but not limited to, rings, necklaces, watches, bracelets, and earrings), headpieces, hats, caps, headbands, hair ties, scrunchies, sunglasses, scarves and/or purses. Thus, it is often hard for individuals to envision what a complete outfit will look like without putting on all of its pieces. Trying on an entire outfit can be time consuming and using a traditional mannequin is often just as time consuming. Furthermore, many individuals do not have space to store a traditional mannequin. What is needed is a device that allows a user to pick out an entire outfit, including various accessories, and see how the entire outfit looks when it is put together without trying it on, yet is small enough to be used in most households.

SUMMARY OF THE INVENTION

An outfit display can include a head section, a shoulder section, a torso section; a bottom (hip/waist) section; an arm section, a neck section, and at least one stabilizing foot. The outfit display can also include necklace guide. In some embodiments the necklace guide is movable.

The head section of the outfit display can include a loop, a hanging hook and/or an earring section. The earring section can be made of a variety of materials including, polystyrene foam, and magnetic materials and/or include a hole configured to hold an earring. In some embodiments the loop is configured to be moveable between an open position and a closed position.

In some embodiments the arm section can be attached to an arm extension and/or a hand section. The arm section can be connected to the arm extension via an arm connector.

In certain embodiments the torso section can include a first torso section; and a second torso section, wherein the second torso section fits into the first torso section such that said torso section is expandable.

BRIEF DESCRIPTION OF THE DRAWINGS

FIG. 1 is an exploded perspective view of an outfit hanger and display.

2

FIG. 2 is a front view of an outfit hanger and display. FIG. 3 is a side view of an outfit hanger and display. FIG. 4 is a front view of an outfit hanger and display hanging from a hook.

5 FIG. 5a is a perspective view of one embodiment of a hook configured to hang an outfit hanger and display.

FIG. 5b is a perspective view of another embodiment of a hook configured to hang an outfit hanger and display.

FIG. 6A is a closeup-front view of a head section showing 10 the loop in an open position.

FIG. 6B is a closeup-front view of a head section showing the loop in a semi-closed position.

15 FIG. 6B is a closeup-front view of a head section showing the loop in a closed position.

DETAILED DESCRIPTION OF PREFERRED EMBODIMENT(S)

FIG. 1 illustrates an exploded perspective view of outfit 20 hanger and display 100. A user can place various garments and/or accessories on hanger 100 to display a particular outfit. In some embodiments, clothes pins or clips are used to hang the garments on hanger 100.

Hanger 100 includes, among other things, head section 4, 25 neck section 8, shoulder section 7, torso section 30, bottom (hip/waist) section 14, and arm section 10.

Head section 4 can include, among other things, loop 5, hanging hook 2, and earring section 6.

In some embodiments hanging hook 2 is configured to 30 hang from chain 78 or S-hooks (see FIG. 4) in conjunction with anchor hanger 70 (see FIG. 4). Chain 78 or S-hooks can be used to allow hanger 100 to grow with the user. In other embodiments, hanging hook 2 can be used to position hanger 100 directly on a wall. In some embodiments, 35 hanging hook 2 can be a clasp, loop or ring.

Earring section 6 is configured to display and/or store 40 earrings. In some embodiments earring section 6 is made of a material such as polystyrene foam or fabric that can be pierced by earrings. In other or the same embodiments, 45 earring section is made of a magnetic material or contains a section of a magnetic material so that it will hold magnetic earrings. In other embodiments, earring section 6 has holes in head section 4 wherein the holes are configured for receiving earrings. In other or the same embodiments, earring section is made of an adhesive material or contains a section of adhesive material configured to hold the 50 earrings.

Loop 5 is configured to display and/or store, among other 55 things, various types of headpieces, hats, headbands, caps and/or helmets. In some embodiments loop 5 is configured to have an open and closed position. When loop 5 is in the open position, it can receive various headpieces, hats, headbands, and the like. Loop 5 can then be placed in a closed position so that the various headpieces, hats, headbands, and 60 the like do not fall off if hanger 100 is moved. In other or the same embodiments loop 5 can also be in a semi-closed position.

FIGS. 6A-6C illustrate a closeup view of head section 4 in which loop 5 is in various stages of being open. FIG. 6A 65 shows the loop in an open position. FIG. 6B shows the loop in a semi-closed position. FIG. 6C shows the loop in a closed position.

Hanger 100 can also include necklace/scarf guides 20 which are configured to store and/or display necklaces or 65 scarves. Necklace/scarf guides 20 are placed on hanger 100 so that when a necklace or scarf is placed on necklace/scarf guides 20 it hangs on hanger 100 roughly where it tradi-

tionally would when being worn by the individual. In some embodiments necklace/scarf guides **20** are able to be moved to various positions to change the way the necklace/scarf drapes on hanger **100**.

Shoulder section **7** is configured to display and/or store various types of outfit tops, including, but not limited to, shirts, tank tops, camis, cardigans, hoodies, sweatshirts, sweaters, strapless tops, dresses, undergarments, and layering of any of the above.

Turning to arm section **10**, in some embodiments arm section **10** can be extended via arm extension **110**. In some embodiments arm section **10** and arm extension **110** are attached to each other by arm connector **115**. Arm connector **115** can be, among other things, a pin, a thumbscrew, a push button, or a magnet. In some embodiments arm section **10** is of a telescoping configuration to expand based on the size of the individual.

Hand section **210** can be configured to hold and/or display various accessories such as, but not limited to bracelets, watches, rings, purses and/or hanger with a matching outfit for a doll. In other or the same embodiments, hand section **210** can be attached to arm section **10** and/or arm extension **110**. In some embodiments hand section **210** is connected to arm section **10** or arm extension **110** with a hand connector (not shown). Hand connector can be, among other things, a pin, a thumbscrew, a magnet, or push button.

Torso section **30** can be configured to expand in size based on the size of the user. In some embodiments, torso section **30** is made up of first torso part **30a** and second torso part **30b**. In some embodiments first torso part **30a** is connected to second torso part **30b** with torso connector **35**. Torso connector **35** can be, among other things, a pin, a thumbscrew, a magnet, or a push button. In other or the same embodiments torso section **30** can be made a single section that is telescoping in nature.

Bottom section **14** is configured to receive various types of outfit bottoms, including, but not limited to, pants, skirts, skorts, shorts, leggings, jeggings, capris, yoga pants, sweats, undergarments and/or layering of any of the above. In some embodiments, bottom section **14** includes logo plate **16**. Logo plate can be used to display, among other thing, the individual user's name.

In some embodiments, hanger **100** includes stabilizing feet **12**. Stabilizing feet **12** aid in keeping hanger **100** from marking up walls/doors, and/or falling forward when the various garments and accessories are held/displayed on it. In some embodiments, stabilizing feet can be capped with rubber or polystyrene foam.

FIG. **2** is a front view of hanger **100**. While FIG. **3** shows a side view of hanger **100** illustrated in FIG. **2**. Stabilizing feet **12** and hanging hook **2**, as described above, are prominent in FIG. **3**.

Turning to FIG. **4**, hanger **100** is shown hanging from anchor hanger **70** via chain **78** or S-hooks. Various embodiments of anchor hanger **70** are illustrated in FIG. **5a** and FIG. **5b**.

FIG. **5a** illustrates anchor hanger **70a** configured to be hung on a wall. In the embodiment illustrated in FIG. **5a** screws and/or nails can be used in conjunction with holes **74** to place anchor hanger **70a** on, among other things, a wall, post, and/or a piece of furniture. Anchor hanger hook **72a** can be configured to hold hanger **100** via chain **78**, S-hooks, or hanging hook **2**. In some embodiments, such as the one illustrated, anchor hanger hook **72a** is turned out to prevent, or at least reduce, chain **78**, S-hooks, and/or hanger **100** from hitting the door and/or wall.

FIG. **5a** illustrates anchor hanger **70b** configured to be hung over a door. Anchor hanger hook **72b** can be configured to hold hanger **100** via chain **78**, S-hooks, or hanging hook **2**. In some embodiments, such as the one illustrated, anchor hanger hook **72b** is turned out to prevent, or at least reduce, chain **78**, S-hooks, and/or hanger **100** from hitting the door and/or wall.

Hanger **100** can be made of a variety of materials including, but not limited to, metals, plastics, wood, PVC, paper, fabric, fiberglass, cardboard, and composite material.

While particular elements, embodiments and applications of the present invention have been shown and described, it will be understood, that the invention is not limited thereto since modifications can be made without departing from the scope of the present disclosure, particularly in light of the foregoing teachings.

What is claimed is:

1. An outfit display comprising:
  - a) a head section comprising
    - i) a loop wherein said loop is configured to be moveable between an open position and a closed position;
    - ii) a hanging hook; and
    - iii) an earring section;
  - b) a torso section;
  - c) a bottom section; and
  - d) an arm section.
2. The outfit display of claim 1 further comprising:
  - e) a neck section.
3. The outfit display of claim 1 further comprising a necklace guide.
4. The outfit display of claim 1 wherein said arm section is configured to be attached to an arm extension.
5. The outfit display of claim 1 wherein said arm section is configured to be attached to a hand section.
6. The outfit display of claim 4 wherein said arm section and said arm extension are connected via an arm connector.
7. The outfit display of claim 1 further comprising a stabilizing foot.
8. The outfit display of claim 7 wherein said stabilizing foot is located on said bottom section.
9. The outfit display of claim 1 wherein said loop is configured to hold a headpiece.
10. An outfit display comprising:
  - a) a head section;
  - b) a torso section comprising
    - i) a first torso section; and
    - ii) a second torso section, wherein said second torso section fits into said first torso section such that said torso section is expandable;
  - c) a bottom section;
  - d) an arm section; and
  - e) a hanging hook configured to hang the outfit display.
11. The outfit display of claim 10 further comprising:
  - f) a neck section.
12. The outfit display of claim 10 further comprising a necklace guide.
13. The outfit display of claim 10 wherein said arm section is configured to be attached to an arm extension.
14. The outfit display of claim 10 wherein said arm section is configured to be attached to a hand section.
15. An outfit display comprising:
  - a) a head section;
  - b) a torso section;
  - c) a bottom section;
  - d) an arm section; and
  - e) a stabilizing foot located on a shoulder section.

- 16. The outfit display of claim **15** further comprising:
  - e) a neck section.
- 17. The outfit display of claim **15** further comprising a necklace guide.
- 18. The outfit display of claim **15** wherein said arm ⁵ section is configured to be attached to an arm extension.
- 19. The outfit display of claim **15** wherein said arm section is configured to be attached to a hand section.
- 20. The outfit display of claim **15** further comprising a second stabilizing foot, wherein said second stabilizing foot ¹⁰ is located on said bottom section.
